DESIGN FOR A COMBINED DESK STAND AND HAND TELEPHONE

Robert H. Hose, Mountainside, N. J., assignor to Bell Telephone Laboratories, Incorporated,
New York, N. Y., a corporation of New York

Application February 26, 1948, Serial No. 144,745

Term of patent 14 years

(Cl. D26—14)

To all whom it may concern:

Be it known that I, Robert H. Hose, a citizen of the United States, residing at Mountainside, in the county of Union and State of New Jersey, have invented a new, original, and ornamental Design for a Combined Desk Stand and Hand Telephone, of which the following is a specification, reference being had to the accompanying drawing, forming a part thereof.

Fig. 1 is a perspective view of a combined desk stand and hand telephone showing my new design;

Fig. 2 is a perspective view of the desk stand alone; and

Fig. 3 is another perspective view, taken at an angle different from that for Fig. 1, of the desk stand and hand telephone.

The characteristic features of my design reside in the portions shown by means of full lines in the drawing.

I claim:

The ornamental design for a combined desk stand and hand telephone, as shown and described.

ROBERT H. HOSE.
